United States Patent Office

Des. 233,848
Patented Dec. 3, 1974

233,848

GOLF ACCESSORY HOLDER

Raymond J. Gotliebowski, 5192 Haverford Drive,
Lyndhurst, Ohio 44124

Filed July 2, 1973, Ser. No. 375,735

Term of patent 14 years

Int. Cl. D21—02

U.S. Cl. D34—5 CB

Fig. 1

Fig. 2

Fig. 3

FIG. 4

FIG. 5

FIG. 6

FIG. 1 is a front elevational view of a golf accessory holder showing my new design;

FIG. 2 is a side elevational view taken from the right of FIG. 1;

FIG. 3 is a bottom plan view;

FIG. 4 is a top plan view;

FIG. 5 is a rear elevational view; and

FIG. 6 is a side elevational view taken from the right of FIG. 5.

I claim:

The ornamental design for a golf accessory holder, as shown.
